UNITED STATES PATENT OFFICE.

JOHN H. WILSON, OF MELBETA, NEBRASKA.

SPOTLIGHT.

Application filed November 30, 1923. Serial No. 677,802.

To all whom it may concern:

Be it known that I, JOHN H. WILSON, citizen of the United States, residing at Melbeta, in the county of Scotts Bluff and State 5 of Nebraska, have invented certain new and useful Improvements in Spotlights, of which the following is a specification.

This invention relates to spot lights such as are commonly used upon automobiles and 10 the like and has for its principal object to generally improve upon devices of this nature by providing a simple and efficient construction, one which is reliable, comparatively inexpensive to manufacture, durable, attrac- 15 tive in appearance, and well adapted to the purpose for which it is designed.

A still further object of the invention is to provide a spot light having a handle provided with a source of illumination that may 20 be utilized as a dash light or the like for an automobile.

With the above and numerous other objects in view as will appear as the description proceeds the invention resides in certain 25 novel features of construction, and in the combination and arrangement of parts as will be hereinafter more fully described and claimed.

In the accompanying drawings:

Figure 1 is a side elevation of the device 30 embodying my invention; and

Figure 2 is a section through the handle portion thereof.

Referring to the drawing in detail it will 35 be seen that 1 designates a shank which is movably mounted in a socket 2 which in the present instance is attached in a well known manner to a wind shield 3. The forward end of the shank supports the usual spot 40 light 4 while the rear end is provided with a handle casing 5 curved so that the portion 6 extends at substantial right angles to the shank 1. This handle casing 5 as is shown to advantage in Figure 2 fits over the rear 45 end of the shank 1 and the lower end of the portion 6 is provided interiorly with a reflector 7 and an electric light socket 8 is mounted in the partition 9 disposed at the upper end of the portion 6 so as to project 50 into the reflector and receive a bulb 10. A contact 11 is provided on the socket 8 and another contact 12 is disposed in spaced relation thereto being mounted in the insulating block 13. One of the leads 14 is attached 55 to the contact 12. The leads pass through an opening 15 provided in that portion of

the handle which is disposed over the shank 1. Some of these leads communicate with the conventional bull's-eye structure 4.

A slot 16 is provided in the curved portion of the handle 5 and a switch plate 17 is mounted adjacent the opening by having a pin 18 projected therethrough. An insulating strip 19 is disposed between the interior surface of the handle casing 5 and the plate 17. The plate 17 is always in contact with the contact 11 and by moving the pin 18 may be slid into engagement with the contact 12 to cause the illumination of the bulb 10.

It is evident that this spot light embodied in the handle is very useful as a dash light for the automobile especially since it can be moved so as to illuminate any desired area of the car. The particular structure of the invention which I have disclosed refers to the preferred embodiment thereof and it is evident that numerous changes in the details of construction, and in the combination and arrangement of parts may be resorted to without departing from the spirit or scope 80 of the invention as hereinafter claimed without sacrificing any of its advantages.

What is claimed is:

1. An illuminating device including a shank, means disposed intermediate the ends of the shank for mounting the shank so that it may be moved at various angles in relation to a support, a spot light at one end of the shank, a handle at the other end of said shank, said handle being in the form of a hollow casing and a source of illumination in said hollow casing.

2. An illuminating device of the class described for use in conjunction with windshields and the like support including a spot light, a shank extended from the spot light, means intermediate the ends of the shank for mounting the shank so that the same may be moved at various angles in relation to the windshield, and a handle projecting angularly from the shank and including means of illumination therein.

3. In a spot light of the class described, means for mounting the spot light so that the same may be moved in various directions, and a handle projected rearwardly from the spot light in the form of a hollow casing having a reflector in the end thereof, and a source of illumination disposed in the reflector.

4. In a spotlight of the class described, means for mounting the spot light so that the

same may be moved in various directions, a handle for the spot light including a hollow casing, a reflector disposed in the end of the casing, an electric socket associated with the reflector, a bulb in the socket, and a switch in the casing associated with the electric socket.

In testimony whereof I affix my signature in presence of two witnesses.

JOHN H. WILSON.
